(57) **CLAIM**

The ornamental design for a watch body, as shown and described.

DESCRIPTION

This application is filed concurrently with U.S. Design application Ser. No. 29/534,046, entitled "Watch Body", and U.S. Design application Ser. No. 29/534,052, entitled "Watch Body", which are both incorporated herein by reference in their entireties.

FIG. 1 is a top perspective view showing a watch body according to our new design from a first end;

FIG. 2 is a bottom perspective view showing the watch body from the first end;

FIG. 3 is an end view of the first end of the watch body;

FIG. 4 is a top perspective view showing the watch body from a second, opposite end;

FIG. 5 is a bottom perspective view showing the watch body from the second end;

FIG. 6 is an end view of the second end of the watch body;

FIG. 7 is a plan view of a top of the watch body;

FIG. 8 is a side view showing a right side of the watch body;

FIG. 9 is a plan view showing a back of the watch body; and,

FIG. 10 is a side view of a left side of the watch body.

The broken line showing of a band represents environment and forms no part of the claimed design. The remainder of the broken lines represent portions of the watch body that form no part of the claimed design.
